UNITED STATES PATENT OFFICE.

NORBERT D. HAMEL, OF GARDNER, MASSACHUSETTS.

PLATE-LIFTER.

No. 806,889.

Specification of Letters Patent.

Patented Dec. 12, 1905.

Application filed May 22, 1905. Serial No. 261,639.

To all whom it may concern:

Be it known that I, NORBERT D. HAMEL, a citizen of the United States, residing at Gardner, in the county of Worcester and State of Massachusetts, have invented certain new and useful Improvements in Plate-Lifters; and I do declare the following to be a full, clear, and exact description of the invention, such as will enable others skilled in the art to 5 to which it appertains to make and use the same.

This invention relates to improvements in plate-lifters.

The object of the invention is to provide a device of this character whereby hot plates, 15 pans, or dishes may be lifted without danger of being burned thereby, said device being particularly well adapted for lifting pie- plates, means being provided whereby a guard is formed around the inner edge of the 20 plate to prevent the article lifted thereby from slipping off the lifter.

A further object is to provide a plate-lifter which will be simple, strong and durable in construction, efficient in operation, and well 25 adapted for the purpose for which it is designed.

With these and other objects in view the invention consists of certain novel features of construction, combination, and arrangement 30 of parts, as will be hereinafter described and claimed.

In the accompanying drawings, Figure 1 is a top plan view of a plate-lifter constructed in accordance with the invention. Fig. 2 is a 35 side view of the same. Fig. 3 is a plan view of the dish-supporting plate removed from the supporting-frame and showing the means whereby the same is connected to said plate, and Fig. 4 is a plan view of the wire frame for 40 supporting said plate.

Referring more particularly to the drawings, 1 denotes a plate which, as here shown, is preferably circular in form and constructed of thin metal. On the edges of the plate 45 at diametrically opposite points are integrally-formed radially-projecting tongues 2, and on the inner side edge of the plate midway between the tongues 2 is formed an integral tongue 3. Arranged on the upper side 50 of the plate adjacent to the inner edge of the same is a supporting-frame 4, said frame being preferably formed of stiff wire and comprises a semicircular attaching portion 5, which is adapted to engage the upper side of

the plate adjacent to the inner edge thereof. 55 Around said attaching portion is clenched the tongues 2 and 3, thereby securely attaching said plate to the frame. Above the edge portion 5 of the frame is arranged a semicircular guard portion 6, said guard portion being formed by bending the wire upwardly and outwardly from the point where it is engaged by the tongues 2. The ends of the wire are brought together above the tongue 2, where the same are twisted, as 60 shown at 7, and bent upwardly and outwardly, as shown at 8. The outwardly-bent ends 8 of the wire are adapted to be inserted into a handle 9, which is preferably formed of wood and is provided on its inner end with a 65 ferrule 10.

By the use of a plate-lifter constructed as herein shown and described hot plates or 70 pans may be lifted from a stove or removed from the oven without danger of burning oneself and is used by inserting the plate 1 beneath the pan or dish, the thin construction of said plate permitting the same to be readily slipped beneath the dish or pan without employing other means for raising the 75 same. The guard 6 formed by the wire supporting-frame prevents the dish or pan from slipping off the inner side of the plate.

From the foregoing description, taken in 80 connection with the accompanying drawings, the construction and operation of the invention will be readily understood without requiring a more extended explanation.

Various changes in the form, proportion, and the minor details of construction may be 85 resorted to without departing from the principle or sacrificing any of the advantages of this invention.

Having thus described my invention, what I claim as new, and desire to secure by Letters Patent, is—

1. A lifter of the character described comprising a plate having formed thereon radially-projecting tongues, a wire supporting-frame secured to said plate by means of said 90 tongues, a guard formed by said supporting-frame, and a handle secured to said frame, substantially as described.

2. A lifter of the character described comprising a circular plate having formed thereon radially-disposed integral tongues, a supporting-frame formed of a single piece of wire 95 bent to form an attaching member around

which is clenched the tongues on said plate, a
guard member arranged above said attach-
ing member, the ends of the wire after form-
ing said guard being twisted and bent up-
wardly and outwardly, and a handle adapted
to receive said outwardly-bent ends of the
wire, substantially as described.

In testimony whereof I have hereunto set
my hand in presence of two subscribing wit-
nesses.

NORBERT D. HAMEL.
